UNITED STATES PATENT OFFICE.

GEORGE RISCHMÜLLER, OF SAN FRANCISCO, CALIFORNIA.

DESIGN FOR A THIMBLE-PLATE.

SPECIFICATION forming part of Design No. 22,917, dated November 28, 1893.

Application filed October 17, 1893. Serial No. 488,430. Term of patent 3½ years.

To all whom it may concern:

Be it known that I, GEORGE RISCHMÜLLER, a citizen of the United States, residing at the city and county of San Francisco and State of California, have invented certain new and useful Improvements in Designs for Thimble-Plates; and I do hereby declare the following to be a full, clear, and exact description of said invention, such as will enable others skilled in the art to which it most nearly appertains to make, use, and practice the same.

My invention relates to a new and original design for thimble plates such as are used for concealing and protecting that portion of a plastered or other wall immediately surrounding a hole through which a rod or shaft projects.

My new design consists of a square, on which are delineated in alto-relievo the following figures and representations. Taking the hole *a*

in the center of the square as an initial point extending upward from it is a stem *b*, at the upper end of which is the representation of a flower *c*. The stem *b* extends also below the hole *a*, and radiating from this lower stem are two volute coils *e. e* extending outward in opposite directions. A semicircular flower wreath depending toward the lower end of the plate connects the terminals of the two volutes, while volute radicles *f. f*, extend upward from the volute coils on each side.

Having thus described my design for thimble plates, what I claim, and desire to secure by Letters Patent, is—

The design for thimble plates, substantially as herein shown and described.

GEORGE RISCHMÜLLER.
